CONVERSION OF HYDROCARBON OILS

Harold V. Atwell, White Plains, N. Y., assignor to
Process Management Company, Inc., New
York, N. Y., a corporation of Delaware

Application October 31, 1934, Serial No. 750,856

6 Claims. (Cl. 196—50)

This invention relates to conversion of hydrocarbon oils and pertains more particularly to a process of cracking hydrocarbons wherein intermediate products of an initial cracking operation 5 are treated in a more effective and efficient manner.

One of the salient objects of the invention is to provide an improved process for cracking hydrocarbon oils which will be more effective and 10 efficient than processes of the same general nature heretofore proposed with concomitant improvement in the quality of products produced.

My invention in its entirety constitutes a series of steps and combination of steps for accomplishing the above and other objects.

For a clear understanding of the objects and nature of my invention reference is now made to the accompanying drawings in which:

Figure 1 is a diagrammatic and schematic plan 20 view of a portion of an apparatus suitable for carrying my invention into effect, and

Figure 1A is a similar view of the remaining portion of the apparatus.

Referring to Figure 1 of the drawings, the number 25 10 designates a charging line having a pump 11 for introducing the oil to be treated into the system. This charging oil should be a relatively clean stock, such as 35 A. P. I. gas oil from a paraffin or mixed based crude which is 30 suitable for drastic cracking treatment for maximum conversion into gasoline constituents. The charging stock before being passed to the cracking zone may be heated to any desired degree by heat exchange with hot products of the system. For example, it will be of advantage to 35 pass the fresh oil through one or both of the heat exchangers 12 and 13, through pipe lines 14, 15, and 16, 17 respectively, wherein the oil is preheated by products from a distilling operation to be hereinafter described.

The fresh charging oil with or without pre-heating in one or both of the heat exchangers 12 and 13 is passed through line 10 to a heating coil 18, located in a furnace 19. The oil, 40 during its passage through the heating coil 18, is heated to a cracking temperature. The passage of oil through the heating coil 18 and the furnace temperature is preferably controlled so as to heat the oil to a relatively high cracking temperature, such as for example of the order of 900-950° F. or more. The oil within the heating coil is also preferably maintained under a relatively high pressure. For example the pressure at the outlet of the coil may range from 500 to 1000 or more pounds per square inch.

The hot cracked products after being subjected to the desired heat treatment within the heating coil 18 are discharged through the transfer line 19' into a separating chamber 20 wherein liquid and residual products separate. The 5 temperature of the products in transfer line 19' is preferably lowered below cracking temperature by introducing a relatively cooler oil into the stream through line 21 before introducing the same into the separator 20. The separator 10 20 is also preferably maintained at materially lower pressure than the coil outlet pressure and to this end the line 19' is provided with a reducing valve 22. For example the pressure in the separator 20 may vary from atmospheric to 15 300 pounds per square inch. If desired a soaking drum (not shown) may be provided between the heating coil 18 and the separator 20.

The charging stock is preferably maintained 20 within the cracking zone for a period sufficient to effect a relatively high percentage conversion in gasoline constituents. For example, the amount of conversion of the original charging stock into gasoline constituents during a single 25 passage through the cracking zone may range from 25 to 40 percent or more of the original charge depending upon the character thereof.

The unvaporized residual products separated 30 within the separator 20 are withdrawn from the bottom thereof through line 23 and, in accordance with one phase of my invention, will preferably be subjected to additional treatment as hereinafter described.

Vapors liberated within the separator 20 pass 35 through line 24 to a fractionating tower 25 and are subjected to fractional condensation therein. The temperature of the tower 25 is controlled so as to condense the vapors higher boiling than the desired motor fuel products produced from 40 the cracking operation. For example, the temperature of the products at the bottom of the tower may range from 650 to 725° F. and the outlet temperature at the top of the tower may range from 350 to 450° F. To this end the tower 45 25 will be provided with cooling and fractionating elements 26 such as bubble trays, disc and doughnut baffles, cooling coils, et cetera. The pressure maintained within the bubble tower may correspond to that maintained within the 50 separator 20, except for the required drop to maintain the desired flow of vapors. I prefer, however, to maintain a substantial pressure such as, for example, 100 to 200 or more pounds per square inch.

Vapors remaining uncondensed within the fractionating tower 25 and which include the desired gasoline constituents pass overhead through line 27 to a condenser 28 (see Figure 1A) wherein 5 the gasoline constituents are condensed.

The condensate formed in the tower 25 may be withdrawn from the bottom thereof through line 29 and a part or all of the condensate after passing through heat exchangers 30, 31 and 32 may 10 be introduced into a solvent extractor 33 and treated as hereinafter described.

However an intermediate trap-out tray 34 may be provided in the tower 25 for separately collecting a lighter condensate fraction. This fraction 15 may be in the nature of kerosene or furnace oil and may be withdrawn from the trap-out tray through line 35 and removed from the system. The condensate passing through the heat exchangers 30 and 31 pass in heat exchange relation 20 with products from the solvent extractor 33, as hereinafter described. Heat exchanger 32 may be provided with lines 36 and 37 for introducing an extraneous medium to further cool the condensate before introducing the same to the extractor 33. The heat exchangers 30, 31, and 32 25 are preferably of the counter-flow type in which the cooling medium passes countercurrent to the flow of the condensate. For simplicity the heat exchangers have been shown merely diagrammatically with the understanding that any suitable type may be employed.

The condensate before being introduced into the solvent extractor 33 should be cooled somewhat below the boiling point of the lighter solvent employed in the solvent extractor 33 as will 35 be more fully explained hereinafter.

The condensate upon being introduced into the solvent extractor 33 is caused to contact with a solvent or solvents and preferably a solvent and 40 an antisolvent capable of separating the condensate into two separate fractions differing from each other in chemical composition; one fraction of which will consist principally of paraffinic hydrocarbons and the other fraction of which will 45 consist principally of nonparaffinic hydrocarbons.

The term "paraffinic" wherever employed in this application is intended to refer to saturated straight and branched chain hydrocarbons, and the term "nonparaffinic" as herein employed is 50 intended to refer to unsaturates and cyclic compounds such as naphthenes and aromatic compounds.

It is preferred to treat the condensate with a solvent or mixture of solvents having a relatively 55 high solvent power for nonparaffinic constituents and a relatively low solvent power for paraffinic constituents. For example, solvents such as dichlor, di-ethyl-ether, furfural, nitrobenzene, sulfur dioxide, phenol, polyhydric alcohols, such 60 as glycerol and ethylene glycol and numerous other oxygenated and chlorinated organic compounds are suitable for this purpose.

In addition to using a solvent of the above character it is also preferred to introduce into the 65 solvent extractor 33 an antisolvent or precipitating agent which may or may not function as a true solvent but which, by increasing the paraffinicity of the material treated, by stripping action, by precipitating action or in some other manner, will aid in effecting a better separation of 70 paraffinic and nonparaffinic components of the condensates. For example, light liquid normally gaseous hydrocarbons such as ethane, propane and butane, and mixtures thereof, may be employed for this purpose. A suitable product may 75

be obtained from a trap-out tray located in the top of a pressure stabilizer used for stabilizing gasoline. Such a product will usually consist principally of propane with small percentages of ethane and butane. For example, a light liquid product from the top of stabilizer 38 (see Figure 1A), which is used for stabilizing gasoline produced as a result of the cracking operation hereinbefore described, may be employed for this purpose. 10

For convenience I have shown the solvent extractor 33 of the countercurrent type wherein the lighter liquid hydrocarbon antisolvent or precipitating agent is introduced into the bottom thereof through line 39 and the nonparaffinic solvent is introduced into the top thereof through the line 15 40, whereas the condensate is introduced into an intermediate section of the extractor.

The condensate upon being subjected to solvent treatment within the solvent extractor 33 20 separates into a lighter paraffinic raffinate fraction and a heavier extract fraction. The raffinate fraction will comprise principally paraffins including the paraffinic fraction of the condensate and the light liquid paraffinic hydrocarbons introduced into the extractor through line 39. The heavier extract fraction will be a solution of the nonparaffinic constituents of the condensate dissolved in the nonparaffinic solvent with small amounts of paraffinic material dissolved therein, the amount of the latter being dependent upon the relative selectivity of the nonparaffinic solvent. 25

The paraffinic or raffinate fraction is withdrawn from the solvent extractor 33 through line 41 and may be passed directly through lines 42 and 43 to the heat exchanger 31, or a portion or all of the raffinate may be first passed through lines 44, 45 and heat exchanger 46 before passing to the exchanger 31. The raffinate in the heat 40 exchanger 46 is passed in heat exchange relation with the vapor products withdrawn from the extract distilling chamber 47 as illustrated. 35

The raffinate upon being passed through either or both of the heat exchangers 31 and 46 may be 45 heated to a temperature sufficient to distill the solvent and the light liquid hydrocarbon antisolvent from the paraffinic fraction of the condensate. After passing through heat exchanger 31 the raffinate then passes through line 48 to a distilling chamber 49 wherein the solvent and antisolvent is distilled from the paraffinic fraction of the condensate. If desired, additional heat for carrying out the distillation may be supplied directly to the distilling chamber, or the 50 raffinate may be passed through an additional heating coil (not shown) before being introduced into the chamber. 55

The nonparaffinic extract, separated within the solvent extractor 33, is withdrawn therefrom through line 51 and is passed through heat exchanger 30 wherein the extract is caused to pass in heat exchange relationship with the hot condensate from the bottom of the fractionating tower 25. The extract may then pass through lines 52, 53, and 54, directly to an extract distilling chamber 47, or a portion or all of the extract may be further heated by passing through heating coil 55 located in the top of the bubble tower 25. The extract introduced into the extract distilling chamber 47 is subjected to distillation to vaporize the nonparaffinic solvent. If necessary, additional heat may be supplied directly to the distilling chamber 47, or the extract may be caused to pass through a further heating coil 70 75

(not shown) before being introduced into the distilling chamber 47.

Distillation within the raffinate distilling chamber 49 and/or the extract distilling chamber 47 may be further expedited by reducing the pressure within the respective chambers. To this end the line 48, connecting heat exchanger 31 with the raffinate distilling chamber 49 may be provided with a reducing valve 56 and the line 54, leading from the heating coil 55 to the extract distilling chamber 47, may be provided with a reducing valve 57.

It is preferred to pass the hot condensate from the bottom of the fractionating tower 25 in heat exchange with the extract from the bottom of the solvent extractor 33 in heat exchanger 30 and thereafter in heat exchange with the raffinate from the top of the extractor in heat exchanger 31 since the solvent in the extract will usually have a higher boiling point than the solvent present in the raffinate and will require a higher temperature to carry out the subsequent distillation of the solvent than that required to carry out the distillation of the lower boiling antisolvent in the raffinate. In practice greater heat economy can be attained by passing the hot condensate from the fractionating tower 25 first in heat exchange relation with that fraction containing the higher boiling solvent and thereafter in heat exchange with the fraction containing the lower boiling solvent or antisolvent.

The amount of solvent and antisolvent employed for effecting the separation will depend upon the character of the original stock, the type of solvent used, the temperature of extraction and the degree of separation desired, and cannot therefore be specified for all conditions. The amount and character of solvents to be used for many different sets of conditions have already been determined, and published information relating thereto is readily available. The amount and character of solvents for other sets of conditions can be determined by simple laboratory experiments.

The paraffinic fraction of the condensate from which the solvent and antisolvent has been distilled within the distilling chamber 49 is withdrawn from the bottom thereof through line 58 and may be returned by means of pump 59 to the inlet side of the heating coil 18 wherein it will be subjected to further conversion treatment with the fresh oil introduced through line 10. This paraffinic fraction may however be withdrawn from the system through line 61 and subjected to a separate cracking operation or other treatment if desired. The vapors liberated in the raffinate distilling chamber 49 pass overhead through line 62 to a condenser 63 wherein a small amount of higher boiling nonparaffinic solvent which may have been dissolved in the raffinate fraction is condensed. The products pass from condenser 63 to a receiving drum 64 wherein the higher boiling liquid solvent separates from the vapors. The liquid is withdrawn from the receiving drum 64 through line 65, which connects with line 40 and is returned to the top of extractor 33. Uncondensed vapors from the receiving drum 64 pass overhead through line 66 and may be separately condensed and again returned to the bottom of the extractor 33, via line 39, but are preferably subjected to further treatment as hereinafter described.

The nonparaffinic fraction of the condensate from which the nonparaffinic solvent has been

distilled in chamber 47 is withdrawn from the bottom thereof through line 67, and after being cooled by heat exchange with the fresh oil for the cracking system in heat exchanger 13 as hereinbefore described, may be withdrawn from the system through line 68, or it may be subjected to further cracking or other treatment as hereinafter described. When subjected to further cracking treatment the hot extract may be bypassed around the heat exchanger 13 through line 69.

The nonparaffinic solvent vapors liberated in the extract distilling chamber 47 pass overhead through line 71, provided with heat exchanger 46, wherein they may be used for heating the raffinate fraction withdrawn from the top of the solvent extractor 33 as hereinbefore described, and heat exchanger 12, wherein they may be used for heating the fresh cracking stock as hereinbefore described, to a condenser 72 (see Figure 1A), wherein the solvent vapors are condensed, and from which the condensate passes to an accumulator tank 73. The solvent from the accumulator tank 73 may then be returned directly to the solvent extractor 33 through line 40, or it may be introduced through line 14 into the upper end of a scrubbing chamber 75 and used for scrubbing the uncondensed vapors from the receiving drum 64 which have been liberated from the raffinate fraction as before described. In the latter case the vapors from the raffinate distilling chamber 49 pass through line 62, condenser 63, condenser receiving drum 64, and line 66, to the bottom of the scrubbing chamber 75. The vapors from receiving drum 64, after being scrubbed by the heavier liquid nonparaffinic solvent in the scrubbing chamber 75, pass overhead through line 76 provided with pump 77 to the bottom section of the stabilizer 38. A by-pass line 78 connecting lines 66 and 76 is provided so that the vapors from the receiving drum 64 may be passed directly to the stabilizing column 38 without passing through the scrubbing chamber 75. The nonparaffinic solvent, after being used for scrubbing the paraffinic solvent vapors in the scrubbing chamber 75, is withdrawn from the bottom thereof through line 79 connecting with line 40 and is returned by means of pump 80 to the solvent extractor 33.

As before mentioned, the vapors remaining uncondensed in the fractionating tower 25 pass overhead through line 27 to a condenser 28 (see Figure 1A) wherein the gasoline constituents are liquefied. The liquid and gaseous products from the condenser 28 then pass to a receiving drum 81 wherein fixed gases and liquid distillate separates. The fixed gases are withdrawn from the receiver 81 through line 82 and the gasoline distillate is withdrawn from the receiving drum 81 through line 83 provided with a heating coil 84 and is preferably passed to the stabilizer 38 wherein the gasoline is subjected to distillation and fractionation. This stabilizer is preferably maintained under relatively high pressure and cooled at the top by pump back of condensed product or liquid of corresponding boiling range from another source, so that the lighter liquid hydrocarbons such as propane and butane are caused to condense at the top of the tower. Vapors remaining uncondensed in the stabilizer 38 pass overhead through line 85 to a condenser 86 for further condensation. Liquid condensed in the condenser coil 86 passes to receiving drum 87 and may be returned through line 88 to the upper end of the stabilizing column as a reflux 75

medium therefor. I may also introduce an additional reflux medium through line 89. The stabilizing tower 38 is preferably provided with a trap-out tray 90 adjacent the upper end thereof for separately collecting a lighter fraction. This fraction should consist principally of propane with relatively small amounts of butane and ethane and olefins of corresponding boiling points, and is withdrawn from the trap-out tray 90 through line 91 and passes to an accumulator tank 92, from which it is passed through line 39 to the lower end of the solvent extractor 33 where it is used as a solvent for carrying out the solvent separation. If desired, additional solvent for effecting this purpose may be introduced into the accumulator tank through line 93.

The gasoline freed of gases within the stabilizer 38 is withdrawn from the bottom thereof through line 94 and is passed to a suitable storage tank 95 as a final product of the system.

The nonparaffinic fraction from which the solvent has been distilled within the extract distilling chamber 47 and which is withdrawn therefrom through line 67 as hereinbefore described is preferably subjected to additional cracking or coking treatment. To this end the nonparaffinic fraction, with or without passing through heat exchanger 13, is conveyed through lines 96 and 97 by means of pump 98 to a separate heating coil 99 located in furnace 101. This non-paraffinic stock is not ordinarily suitable for drastic cracking conditions such as that maintain in the heating coil 18 and it is preferred, therefore, to maintain the heating coil 99 under more mild cracking conditions than that maintained for heating coil 18. For example, the nonparaffinic fraction, during its passage through the heating coil 99, may be heated to a temperature from 800 to 900° F. and for a period of time sufficient to convert not more than 20% of the original stock into motor fuel constituents. Furthermore, it is preferred to maintain this oil during its passage through the heating coil under relatively low pressure as compared to that in the heating coil 18. This cracking operation may for example be maintained under cracking temperature in which the pressure at the outlet of the coil may vary from substantially atmospheric to 200 pounds or more per square inch. The products from the heating coil 99 pass through transfer line 102 to a reaction or coking chamber 103.

In accordance with one phase of my invention the heating coil 99 and subsequent chamber 103 may be operated as a coking unit, in which case the residuum is not withdrawn continuously from the soaking chamber 103, but is allowed to remain therein until it is converted to coke. In accordance with this mode of operation, alternate chambers 103 are preferably provided so that when one chamber is filled with coke the second may be used while the first is cleaned. The vapors from chamber 103 pass overhead through line 104 to a fractionating column 105. The operating conditions maintained within the chamber 103 may be such as to produce a liquid residuum rather than a solid deposit as hereinbefore described. In this event, the liquid residuum will be withdrawn from the chamber 103 through line 106. The chamber 103 is also provided with a manhole 107 for removing solid deposits, and suitable coke removing apparatus (not shown) may be used in conjunction therewith.

The vapors formed as a result of the cracking or coking operation are subjected to fractionation in the tower 105 to condense a heavier frac-

tion boiling above the desired endpoint of the gasoline distillate. Vapors remaining uncondensed in the fractionating tower 105 and containing desired gasoline constituents pass overhead from the tower 105 through line 108 to a condenser coil 109 wherein the gasoline constituents are liquefied. The liquid and vapor products from the condenser coil 109 pass to a receiving drum 111 wherein the liquid distillate and fixed gases separate. The fixed gases may be withdrawn from the receiving drum 111 through line 112 and the gasoline distillate may be withdrawn through line 113. This gasoline distillate may be withdrawn from the system through line 114 as a final product thereof, or it may be passed through line 115 to the stabilizing tower 38 for further treatment therein. The heavier condensate fraction formed in the fractionating tower 105 is withdrawn from the bottom thereof through line 116 and may be returned through line 117 to the heating coil 99 for further conversion treatment.

In accordance with one phase of my invention, however, I prefer to treat this fraction in the manner hereinafter described.

As beforementioned, the residuum resulting from the cracking operation is withdrawn from the separator 20 through line 23 (see Figure 1). Heat may be extracted from the residuum by passing the same through heat exchanger 118 wherein it comes in heat exchange relationship with other products of the system. As shown, the hot residuum is passed in heat exchange with a part or all of the paraffinic fraction from line 58 which passes through the heat exchanger via lines 119 and 121. This residuum, after being cooled in heat exchanger 118, may be withdrawn from the system through line 122, if so desired.

It is preferred, however, to subject a part or all of this residuum to treatment with a liquefied, normally gaseous hydrocarbon, such as liquefied ethane, propane, or butane, or mixtures thereof to effect further separation and subject the separated components to further treatment as hereinafter described. To this end, the residuum is passed through line 23, to a mixing chamber 123, wherein the residuum is caused to contact with a light liquid hydrocarbon of the character above described. Additional cracked tar from other sources may be introduced into the mixing chamber 123 through line 124 and be subjected to additional treatment as hereinafter described. As shown, the liquefied hydrocarbons such as ethane, propane, butane, or mixtures thereof are introduced through line 125 into the mixing chamber 123. As further illustrated, this liquefied hydrocarbon may be a light product withdrawn from the upper trap-out tray 90 of the stabilizer 38 (see Figure 1A) in which case a portion of the light liquid hydrocarbon, from line 39, may be diverted through lines 126 and 125 to the mixing chamber 123. The mixing chamber 123 is provided with suitable mixing elements, such as baffles or stirring blades to cause an intimate mixing of the residuum and light liquid hydrocarbons. The mixture from the mixing chamber 123 passes through line 127 to a settling tank 128 wherein it separates into two component layers differing in specific gravity and boiling range. The mixing chamber 123 and settling chamber 128 will be maintained under temperature and pressure conditions which will retain the light hydrocarbons in liquid form. The amount of heavy lower layer precipitated by the light liquid hydrocarbon will depend upon 75

the relative proportion of light liquid hydrocarbons used and the temperature of the separation. It is preferred to carry out the separation under conditions which will precipitate a relatively small proportion of the original residuum as a lower layer, which is suitable for coking treatment. For example, when using a light liquid fraction from the top of the stabilizer 38 comprising principally propane as a separating agent equal volumes of solvent medium and residuum may be used and the separating temperature controlled to produce an extremely heavy layer at the bottom of the extractor, which may comprise from 5 to 20% of the residuum treated. The heavy asphaltic material separated within the settling tank 128 is withdrawn therefrom through line 129 and may be withdrawn from the system through line 131, if so desired.

In accordance with another phase of my invention, this heavy fraction from the bottom of settling tank 128 is passed through lines 129 and 132 to the jointure of lines 96 and 97 and there combined with the extract from the bottom of the distilling chamber 47 after which it is subjected to relatively mild cracking or coking treatment in heating coil 99 and chamber 103 as before described. If desired, however, this heavy fraction, or the extract fraction, may be subjected to cracking or coking treatment independently of the other fraction in heating coil 99 and chamber 103 or in a separate unit (not shown) so that each of these fractions can be subjected to individual treatment depending upon the characteristics thereof.

The lighter fraction separated in the settling tank 128 is withdrawn from the top thereof through line 133 and may be withdrawn from the system through line 134. In accordance with another phase of my invention, however, this fraction is preferably mixed with a heavy condensate from the bottom of fractionating tower 105 (see Figure 1A) and the mixture then passed to a solvent extraction apparatus for separating the composite stream into paraffinic and nonparaffinic constituents.

As shown in Figure 1, line 116, leading from the bottom of fractionating tower 105 (Figure 1A) and line 133, leading from the top of settling tank 128, are interconnected so that the composite stream may be passed through line 135 to the solvent extractor 38 wherein it commingles with the condensate from the bottom of the fractionating tower 25. While I have shown a common solvent extractor 38 for separating both the condensate from the fractionating tower 25 and the composite stream just mentioned into paraffinic and nonparaffinic fractions, it is understood that the composite stream may be subjected to a separate solvent extraction treatment. When passing the lighter fraction, containing light liquid hydrocarbons, from the top of settling tank 128 to the solvent separator 38, relatively little or no light liquid hydrocarbons need be introduced into the bottom of solvent extractor 38 since the overhead from the settling tank will contain sufficient light liquid hydrocarbons. It is preferred, however, to introduce a small amount of light liquid hydrocarbons into the bottom of the extractor 38 to operate as a stripping medium therein. The paraffinic and nonparaffinic fractions of the composite stream separated in the extractor 38 may then be treated along with and in the same manner as the fractions formed from the condensate withdrawn from the

fractionating tower 25 as hereinbefore described.

It has further been found that a blend of asphaltic material resulting from separating cracked tar as hereinbefore described and nonparaffinic extract resulting from a solvent separating treatment makes an excellent water proofing, wood preserving and paving material which has remarkable penetrating properties.

In accordance with one feature of the invention, a portion or all of the nonparaffinic fraction from the bottom of distilling chamber 47 is withdrawn from line 96, through line 143 and is blended, in line 144 and tank 145, with the heavy asphaltic fraction from the bottom of settling tank 128, withdrawn from line 132, through line 146, connecting with line 143.

Having described the preferred embodiment, it will be understood that my invention embraces such other variations and modifications as come within the spirit and scope thereof and that it is not my intention to dedicate any novel subject matter or unnecessarily limit my invention except to distinguish from prior art.

I claim:

1. In the pyrolytic treatment of hydrocarbon oil wherein the fresh charging oil is subjected to cracking treatment and the cracked products thereafter separated into vapors and unvaporized residuum; the improvement which comprises treating the residuum resulting from said separation with a liquefied, normally gaseous, hydrocarbon to precipitate a heavy fraction therefrom, separating said heavy fraction from supernatant liquid, treating said supernatant liquid with a solvent capable of separating the same into a paraffinic component and a nonparaffinic component and subjecting said paraffinic component to said first mentioned cracking treatment to convert the same into hydrocarbons suitable for motor fuel.

2. In the pyrolytic conversion of hydrocarbon oil wherein fresh charging oil is subjected to cracking treatment and the cracked products thereafter separated into vapors and unvaporized residue; the improvement which comprises treating the residue resulting from said separation with a liquefied, normally gaseous, hydrocarbon to precipitate a heavy fraction therefrom, separating said heavy fraction from supernatant liquid, heating said heavy fraction so separated to a temperature and for a period sufficient to convert the same to vapors and a substantially solid residue, fractionating said last-named vapors to form a condensate and an overhead vapor fraction, combining said last-mentioned condensate with said supernatant liquid, treating said composite mixture with a solvent capable of separating the same into a paraffinic fraction and a nonparaffinic fraction and subjecting said paraffinic fraction to further cracking treatment at a temperature and for a period of time sufficient to convert the same into hydrocarbon suitable for motor fuel.

3. In the pyrolytic conversion of hydrocarbon oil wherein a fresh charging oil is subjected to cracking conditions and the cracked products thereafter separated into vapors and unvaporized residuum; the improvement which comprises treating the residuum so separated with a liquefied, normally gaseous, hydrocarbon to precipitate a heavy fraction therefrom, separating said heavy fraction from supernatant liquid, treating the supernatant liquid with a solvent capable of separating the same into a paraffinic fraction and a nonparaffinic fraction, combining

said nonparaffinic fraction with said heavy fraction and subjecting said combined mixture to a temperature and for a period sufficient to convert said mixture into vapors and an unvaporized substantially solid residue.

4. In the pyrolytic treatment of hydrocarbon oil for producing motor fuel wherein fresh charging oil is subjected to cracking treatment, the cracked products then separated into vapors and unvaporized residue, the vapors so separated then fractionated to condense higher boiling constituents thereof from an overhead vapor fraction, the improvement which comprises treating said last-named condensate with a solvent capable 15 of separating the same into a paraffinic fraction and a nonparaffinic fraction, treating said residue with a liquid, normally gaseous, hydrocarbon to precipitate a heavy fraction therefrom, separating said heavy fraction from supernatant liquid, subjecting said nonparaffinic fraction and said heavy fraction to a temperature and for a period sufficient to convert the same into vapors 20 and a substantially solid residue.

5. In the pyrolytic treatment of hydrocarbon oil for producing motor fuel wherein higher boiling hydrocarbons are subjected to cracking conditions, the cracked products then separated into vapors and unvaporized residue, the vapors fractionated to condense higher boiling hydrocarbons 25 therefrom and the uncondensed vapors then subjected to a second condensing step to liquefy a final distillate product; the improvement which comprises treating said first-mentioned condensate with a solvent capable of separating the same into a paraffinic fraction and a nonparaffinic fraction, treating said residue with a liquid, normally gaseous, hydrocarbon to precipitate a heavy fraction therefrom, separating said heavy fraction from supernatant liquid, subjecting said nonparaffinic fraction and said heavy fraction to a temperature and for a period sufficient to convert the same into vapors and a substantially solid residue.

sate with a solvent capable of separating the same into a paraffinic fraction and a nonparaffinic fraction, treating said residue with liquid, normally gaseous, hydrocarbons to precipitate a heavy fraction therefrom, separating said heavy 5 fraction from supernatant liquid, combining said heavy fraction with said nonparaffinic fraction and subjecting the combined mixture to a temperature and for a period sufficient to convert the same into vapors and unvaporized substantially 10 solid residue, treating said supernatant liquid with a solvent capable of separating the same into a paraffinic and nonparaffinic fraction, and subjecting said paraffinic fraction to said cracking conditions first mentioned.

6. In the solvent treatment of hydrocarbon oil wherein the oil is separated into a paraffinic component and a nonparaffinic component; the improvement which comprises treating said oil with a light liquid, normally gaseous, hydrocarbon and with a nonparaffinic solvent having a higher boiling point than said last-mentioned liquefied hydrocarbon, whereby the paraffinic raffinate fraction contains the light liquid normally gaseous hydrocarbon and a nonparaffinic extraction contains the nonparaffinic solvent, distilling said paraffinic fraction to liberate said light, normally gaseous, hydrocarbons, and scrubbing the light hydrocarbons liberated from said last-named distilling operation with said non-paraffinic higher boiling solvent.

HAROLD V. ATWELL.
